FLORIO G. FLOSI, OF CHICAGO, ILLINOIS

DISPENSING POWDER PUFF

Application filed March 7, 1932. Serial No. 597,384.

This invention relates to powder puffs and it has particular relation to powder dispensing puffs having means for maintaining a fresh and adequate supply of powder for the user.

Commonly used powder puffs are employed in conjunction with separate receptacles containing powder, or in conjunction with compartments in purses, handbags, vanity compacts, and the like, and frequently powder was wasted or spilled upon the clothing or other articles during its application to the puff and to the face. In utilizing devices of this kind it is necessary to press or dip the puff into the receptacle in order to obtain the proper supply of powder for facial or other application in a well known manner. The dipping of the puff into the receptacle not only wastes the powder, but also involves uneven application upon the puff as well as upon the face. Likewise, it is likely to drop upon articles of clothing or upon the floor which will then require brushing or cleaning.

In the type of powder puff disclosed herein a resilient porous core having a powder receiving cavity therein is provided inside a flexible cover of suitable material such as that of which the outer layer of a conventional powder puff is composed. The cover is provided with closure devices to insure access to the interior of the puff to facilitate replenishing the supply of powder or to facilitate replacing elements of the puff. With respect to the latter feature, either the cover or the porous core may be replaced.

In the drawing:

Fig. 1 is a perspective of an improved powder puff;

Fig. 2 is a perspective of a powder puff, closure elements thereof being loosened to illustrate the interior structure and the manner in which the closure elements are manipulated;

Fig. 3 is a cross section, on a larger scale, of the powder puff;

Fig. 4 is a perspective of a resilient porous core for the powder puff;

Fig. 5 is a perspective of another form of improved powder puff; and

Fig. 6 is a perspective of the closure elements of the powder puff shown by Fig. 5.

Referring to Figs. 1 to 4, a powder puff 10 is shown comprising complementary cover sections 12 and 13 having their edges inwardly turned and secured to provide a seam 14 formed by sewing or by other suitable fastening means. Although the edges of the sections are turned inwardly they are not hemmed but form marginal portions 15 and 16 which are coincident with the seam 14 along slightly more than half the perimeter of the puff. A strap 17 incorporated in opposite seam portions of the puff extends diametrically across its surface and serves as a handle for the puff.

An opening 18 defined by the edges of the section which are not seamed is provided with flexible closure elements 19 each of which has one end secured adjacent the end of the strap in the seam 14 and is threaded progressively through eyelets 20, 21, 22, 23, 24, 25 and 26. These closure elements are in the form of draw strings and by drawing them the eyelets 20-21, 22-23 and 24-25, respectively, are drawn against each other to close the opening 18 and to provide the smoothly closed edge portions throughout the circumference of the powder puff. The closure elements are then tied as indicated at 30.

By opening the section as shown in Fig. 2 it is then in position to receive a flexible porous core 32 composed of sponge rubber, textile, or any other suitable material having the central cavity 33 therein that is covered by a central portion of the section 12 and is adapted to contain a supply of powder 34. A plurality of openings 36 communicating through the section 12 with the cavity 33, provides for dispensing the powder.

- therethrough. These openings are of suitable size to dispense proper amounts of powder. If desirable the openings 36 can be made relatively large and a sheet of gauze 37 or other mesh material can be secured to the inner surface of the section 12 to overlie the cavity 36, thus facilitating the dispensing of the powder. Since the core 32 is resilient, it maintains the powder puff in a desirable shape and in soft yieldable condition. Likewise, inasmuch as air is entrapped in the porous structure of the sponge rubber, the powder can be forced out by pressure.
- 15 In the form of the invention shown by Figs. 5 and 6, the same construction of sections 12 and 13 is provided together with the resilient core 32. However, in this form the draw strings 19 are omitted and a pair of closure members 38 and 39 are provided which comprise arcuate wires having hinged end connections 40. These wires are resilient and the central portion of the wire 38 is bent into an offset fastener 42 of U-shape 25 which springs or snaps over the central portion of the wire 37, as indicated at 43. The wire 38 is disposed within the cover 12 and fits snugly inside the marginal portion 15, the fastener projecting through the marginal portion, as indicated at 44. The other wire 39 is disposed within the cover 13 and thus when the fastener is snapped to close the covers, there is a thickness of cover 13 between the fastener 42 and the wire 39. The end 35 connections 40 between the wires are secured in the same portion of the cover adjacent the extremities of the opening 18. As shown by Fig. 5 the strip 17 has been omitted and in this form of the invention, the powder may 40 be dispensed through the opening 36 and then distributed properly over the powdered surface by turning the puff and applying the reverse side which does not have dispensing openings.
- 45 From the foregoing description it will be apparent that the cover sections 12 and 13 can be removed, cleaned, and replaced upon the sponge rubber, or the sponge rubber can be easily washed or replaced. There is no 50 danger of wasting the powder or spilling it upon clothing or other articles and uniform dispensing of the powder is insured.
- Although only two forms of the invention have been shown and described in detail, it 55 will be apparent to those skilled in the art that the invention is not so limited but that various changes may be made therein without departing from the spirit of the invention or from the scope of the appended claims.
- 60 What I claim is:
1. A powder puff comprising a hollow cover, said cover having an opening therein, means for opening and positively closing the opening, a yieldable powder receptacle disposed inside the cover and removable

through said opening, said cover having perforations communicating with the receptacle for dispensing powder.

2. A powder puff comprising a pair of cover members provided with complementary 70 inturned marginal portions, said marginal portions being secured together along a major portion of their length, to provide a core receiving mouth, closure means extending along the marginal portion adjacent the secured portion to close said mouth, and a powder receptacle disposed between the cover members and replaceable through said mouth for dispensing powder through one of the cover members.

3. A powder puff comprising a pair of cover members provided with complementary inturned marginal portions, said marginal portions being secured together along a major portion of their length, a closure member interlaced from one marginal portion to the other beyond said major portion, and a resilient porous member having a cavity therein disposed between the cover members, one of the cover members having perforations 85 communicating with the cavity for dispensing powder from the cavity through the perforations.

4. A powder puff comprising a pair of cover members provided with complementary 90 inturned marginal portions secured permanently along the major portion of their length, a pair of closure members hinged together adjacent the extremities of the permanently secured marginal portions; each closure member being enclosed between one inturned portion and the adjacent wall of the cover, a snap fastener on one of the closure members for engaging the other closure member whereby the cover members are closed, and a sponge rubber core removably disposed between the cover members and having a powder containing cavity therein, one of the cover members having perforations 95 communicating with the cavity for dispensing powder therefrom.

5. In a dispensing powder puff, a sponge rubber core having pores interspersed substantially uniformly throughout and adapted to receive powder and expel it when pressed, said porous core having a relatively large cavity for receiving a bulk of powder to be dispensed both from the cavity and through the pores.
